UNITED STATES PATENT OFFICE.

SIGMUND FREY, OF SAN DIEGO, CALIFORNIA, ASSIGNOR OF ONE-THIRD TO GEORGE E. TOMS AND ONE-THIRD TO THOMAS P. BLAIR, BOTH OF SAN DIEGO, CALIFORNIA.

GRAVITY-HINGE.

1,034,008.

Specification of Letters Patent. Patented July 30, 1912.

Application filed June 15, 1911. Serial No. 633,310.

To all whom it may concern:

Be it known that I, SIGMUND FREY, a subject of the King of Hungary, residing at San Diego, in the county of San Diego and State of California, have invented certain new and useful Improvements in Gravity-Hinges; and I do declare the following to be a full, clear, and exact description of the invention, such as will enable others skilled in the art to which it appertains to make and use the same.

This invention relates to improvements in gravity hinges.

One object of the invention is to provide a hinge having an improved construction and arrangement of operating devices whereby when the door to which the hinge is connected is swung open to about right angles, the same will remain in this position until started back whereupon the operating devices of the hinge will be actuated by gravity or the weight of the door to completely close the same.

With this and other objects in view, the invention consists of certain novel features of construction, combination and arrangement of parts as will be more fully described and particularly pointed out in the appended claim:

In the accompanying drawings: Figure 1 is a plan view of my improved hinge showing the position of the parts when the hinge is open; Fig. 2 is a similar view showing the hinge closed; Fig. 3 is a rear edge view of the hinge closed as shown in Fig. 2; Fig. 4 is a cross sectional view on the line 4-4 of Fig. 1; Fig. 5 is a plan view of the hinge members with the pintle and operating members removed; Fig. 6 is a perspective view of one of the hinge operating devices removed; Fig. 7 is a similar view of the other leaf operating device; Fig. 8 is a view similar to Fig. 3 with parts broken away and in section showing a modified arrangement of the hinge operating devices.

My improved hinge comprises members 1 and 2, in the form of flat leaves or plates. The plate or leaf 1 has formed on its inner edge a vertical knuckle 3 below which is formed an elongated lug 4. At the lower end of the lug the edge of the plate has formed therein a shallow recess 5.

The member 2 has formed on its inner edge near its upper end a short vertical knuckle 6 and near its lower end a longer

knuckle 7. Above the knuckle 7 is formed an elongated lug 8 and above said lug is formed a shallow recess 9.

Engaged with the knuckles 3, 6 and 7 of the hinge members is a pintle or hinge pin 10 having reduced threaded ends 11 on which are screwed knobs or heads 12. On the pin or pintle 10 and engaging the recesses 5 and 9 are lower and upper collars 13 and 14 which have the opposite sides of 85 their engaging ends cut away to form cam or inclined surfaces 15 and 16 which are adapted to engage when the hinge is opened or closed. When the door is opened to a position at right angles to its casing and the hinge members brought in line with each other the inclined surface of the collar 14 on the door member of the hinge will have ridden up the inclined surface of the collar of the frame member of the hinge and the 75 flat surfaces of the collars thus brought into engagement whereupon the door will remain open until swung back far enough to again bring the inclined surfaces into engagement. When thus engaged, the weight 80 of the door will force the inclined surface of the collar of the door member of the hinge to slide down the inclined surface of the co-acting collar of the frame member, thereby swinging the door to a closed position.

The collars 13 and 14 have formed in one side thereof vertical slots 17 with which the lugs 4 and 8 of the hinge members or leaves are adapted to be engaged, whereby said 90 collars are turned by the hinge members to bring the inclined surfaces of the collars into and out of engagement.

In Fig. 8 of the drawings is shown a slightly modified form of the hinge. In 95 this form the collars 13 and 14 are shown to be counter-bored in their outer ends to form sockets 18 whereby the eyes or loops of the hinge members are adapted to set into the sockets 18. This construction and 100 arrangement braces the parts and is intended more particularly for large heavy hinges.

From the foregoing description taken in connection with the accompanying drawings, the construction and operation of the 105 invention will be readily understood without requiring a more extended explanation.

Various changes in the form, proportion and the minor details of construction may be resorted to without departing from the 110.

principle or sacrificing any of the advantages of the invention as defined in the appended claim.

Having thus described my invention what

5 I claim is:—

A hinge comprising door and frame members having coöperating knuckles on their adjacent edges, a pintle adapted for insertion in said knuckles to hingedly and slidably connect said members, lugs on the opposed edges of said hinge members arranged in different planes, collars pivotally

mounted on said pintle between said knuckles, and provided with longitudinal slots for engagement with said lugs, said 15 collars having inclined co-acting faces.

In testimony whereof I have hereunto set my hand in presence of two subscribing witnesses.

SIGMUND FREY.
